United States Patent Office.

NEWEL CARPENTER AND JAMES HUTCHINSON, OF WHITE CREEK,
WISCONSIN.

Letters Patent No. 66,793, dated July 16, 1867.

IMPROVEMENT IN HOP-PRESS.

The Schedule referred to in these Letters Patent and making part of the same.

TO ALL WHOM IT MAY CONCERN:

Be it known that we, N. CARPENTER and JAMES HUTCHINSON, of White Creek, in the county of Adams, and State of Wisconsin, have invented certain new and useful improvements in Baling-Presses; and we do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use our invention, we will proceed to describe it.

Our invention consists in making a new and improved press for pressing hops or similar substances, so that they may be conveniently baled for transportation. In the drawings—

Figure 1 is a longitudinal vertical section.

Figure 2 is a cross vertical section, and

Figure 3 is a detached view.

In constructing our hop-press we take two pieces of wood K K, made of the desired shape and size, for the base, and between and near their ends pivot two uprights B B. Over the pieces K K, and between the uprights B B, we fasten the boards h for the bottom of the press. There are two of these uprights B B at each end of the press, and they are made so as to stand parallel with and a short distance from each other. The intervening space at their lower ends is filled as shown in fig. 2. Between the pairs of parallel uprights B B we place a beam, C, having a tenon at each end of the proper size to pass through the openings or space between each pair of uprights and long enough to extend beyond them and receive a bolt, f. The beam C is made to move vertically between the uprights B B. On the upper side of the beam C we fasten iron plates e, which extend from its ends towards its centre, and are in length about one-third of the length of the beam. On the inside of each upright B we fasten an iron plate, D, having ratchet-teeth on its outer surface between the uprights, as well as on its side facing the inside of the press. These plates D are made to extend from the top of the uprights downwards about one-third or one-half their length. On the upper side of the beam C we place pawls a, which are held against the ratchets on the side of the plates D facing inward, by the springs b. We make a double-headed lever G, and to its lower head pivot a flanged roller, d, and to its upper head hinge a block, F, as shown in fig. 1. This block is so made that it will slide between the ratchet-plates D between each pair of the uprights B, and is provided with grooves in which these plates run, and by which the uprights are prevented from spreading as shown in fig. 2. This block is also provided with two dogs e hinged at i, and held against the ratchet-plates D by the springs j, as shown in fig. 3. The sides I I of the press are hinged at g so that they may be held and fastened by a catch or hook, or let down, at pleasure.

It will be noticed that each end of the press has the same structure and adaptation of parts for operating it.

After the press is filled and the sides closed, the beam C will rest on the upper surface of the filling. Then we pull back the lever G till the rollers d cease to bear upon the beam C, which is held in its place by the pawls a, and at the same time pinch the dogs e together and shove down the blocks F. As soon as they are released they catch into the ratchet-plates D and hold the blocks where they are placed. Now we bear down on the levers and push them forwards. As the rollers d pass along the plates e the heads of the levers are brought into a line with the uprights B and the beam C is pressed down, and as it is pressed down the pawls a catch into the ratchet-plates and hold it. After the rollers pass beyond the line of the uprights they cease to press. The dogs are now pinched again and the blocks pushed down still further; then we raise the levers up and pull them towards us, and a further pressing is done in the same manner, and the hops or other substance pressed into shape for baling.

Having thus described our invention, what we claim, is—

A novel arrangement for applying lever power to press hops or similar substances, consisting of the blocks F provided with the dogs e, and the hinged lever G provided with the flanged rollers d, in combination with the ratchet-plates D, beam C, and pawls a, when arranged to operate as described.

NEWEL CARPENTER,
JAMES HUTCHINSON.
